WILLIAM H. SMITH AND ROLLIN S. EDDY, OF LA CROSSE, WISCONSIN,
ASSIGNORS TO THEMSELVES, SETH DEAN, AND HENRY MERRILL.

Letters Patent No. 77,225, dated April 28, 1868.

IMPROVED MACHINE FOR CUTTING KEY-SEATS.

The Schedule referred to in these Letters Patent and making part of the same.

TO ALL WHOM IT MAY CONCERN:

Be it known that we, WILLIAM H. SMITH and ROLLIN S. EDDY, of La Crosse, in the county of La Crosse, and State of Wisconsin, have invented certain new and useful Improvements in Machines for Cutting Key-Seats in wheels, pulleys, &c.; and we do hereby declare that the following is a full, clear, and exact description thereof, reference being had to the accompanying drawings making part of this specification, and to the letters of reference marked thereon, like letters indicating like parts wherever they occur.

To enable others skilled in the art to construct and use our invention, we will proceed to describe it.

Our invention relates to machines for cutting key-seats in wheels, pulleys, and similar articles of machinery, and consists in a novel construction and arrangement of mechanism for that purpose. In the drawings—

Figure 1 is a longitudinal vertical section, on the line $z z$ of fig. 3.

Figure 2 is a view of rear elevation.

Figure 3 is a top plan view.

Figure 4 is a longitudinal vertical section on the line $y y$ of fig. 3; and

Figure 5 is a transverse vertical section on the line $z z$ of fig. 3.

In constructing our machine, we make a hollow cylindrical column, A, with a wide slot, a , in front, extending nearly its entire length, and a narrower and shorter one, b , in the rear. Within the column A we place a rack, B, arranged to move vertically, and having pivoted to its upper end a cutting-tool, C, having a series of saw-teeth on its cutting-edge, and constructed so as to taper from its upper to its lower end, in order that, in descending, it may feed itself forward in the slot a , in the pin d , as clearly shown in fig. 1. The slotted pin d , through which the cutting-tool C thus moves vertically, we adjust, in any suitable manner, firmly into the head of the column A, as shown in figs. 1, 2, and 3.

The back side of the rack B we construct, as shown in fig. 1, so that it may slide in the slot b easily, and yet be arranged so as to have only a vertical movement, with a portion of it projecting outside of the column A, and having rigidly attached to it an eye or loop, e, to slide on the rod f, having two adjustable collars, $g' g''$, as shown in figs. 1 and 2, for a purpose hereinafter explained.

We mount the shafts g and h in suitable bearings attached to the column A, and in the standard D, as shown clearly in figs. 2 and 3. The shaft h is above and in the rear of the shaft g , as shown in figs. 1, 2, 3, and 4, and at a suitable distance from one another for the gearing which is to be placed upon them. The shaft h extends in front of the slot a , in the column A, and has rigidly attached to it a pinion, E, which gears into the rack B.

Near the opposite end of the shaft h is a large gear-wheel, F, also rigidly attached, so as to turn at the same time with the shaft h and the pinion E.

Between the wheel F and the pinion E we place a sleeve upon the shaft h , and to this sleeve rigidly attach the gear-wheel G and pinion I, so that they must turn together.

On the shaft g the wheels are arranged as clearly shown in fig. 5. The bearings, i , of one end of the shaft g are in the standard D, and the bearings, j , of the opposite end are attached to the column A.

On the shaft g , and within the bearings j , we place a sleeve, which extends far enough on each side of the bearings j to receive and have rigidly attached to it the driving-wheel K and pinion L, which is arranged to gear into pinion M, which turns loosely on a short journal or shaft attached to the column A. The pinion M gears into the wheel G, as clearly shown in figs. 1 and 2, and is made to move loosely, so as to make the wheel G move in an opposite direction from the pinion L.

On the other end of the shaft g , within and next to its bearings, we rigidly attach the pinion N, which gears into the wheel F, and on the same shaft, and next to the pinion N, we place the wheel O, so as to turn easily about the shaft.

Between the wheel O and pinion L, on the shaft g , we place an adjustable clutch, P, arranged to move longitudinally on the shaft, and provided with a feather, m, which moves in a slot, n, in the shaft g , and prevents

it from turning about the shaft. The clutch P is made so as to engage rigidly, by means of pins ξ , with the pins λ , on the wheel O, and also to clutch, by a friction-bearing, with the pinion L, as clearly shown in fig. 5, and in this manner the end of the clutch P opposite that which engages with the wheel O is made beveling, to fit into a corresponding bevel groove in the pinion L, so as to form a friction-clutch with it, as shown in fig. 5. By this means the clutch P is made to engage with the wheel O, when moved in one direction, or with the pinion L, when moved in the other.

The clutch P is operated automatically or by hand, by means of an elbowed lever. This lever is clearly shown in figs. 2 and 4. Its middle shaft, g , is mounted in bearings, p , under the mechanism already described, and in a line at right angles with the line of the shaft g . At the end of the shaft g , directly under the clutch P, is attached rigidly a shifter, r , at right angles, vertically, and arranged to operate the clutch, as shown in figs. 4 and 5. To the other end of the shaft g is attached rigidly a handle, Q, and at right angles to it, horizontally and rigidly, an arm, S, which has pivoted to its opposite end, vertically, the rod f , which will move vertically in the guide t , attached to the column A, as shown in figs. 1 and 2.

The rod f is provided with two adjustable collars, g' and g'' , which are arranged so as to be operated against by the eye or loop, e , of the rack B, so as to move the rod f either up or down.

We make the rake of the saw-teeth in the cutter C to correspond with the depth it is desired to cut the key-seat, and just above the point where the cutter C is attached to the rack B, we fasten a guard, u, which catches the chips and turns them, so that they will run outside of the column, and so not interfere with the mechanism.

In operating our machine, we place the wheel, pulley, or other article in which we desire to cut a key-seat, over the cutter C, and down on the pin d . We then adjust the collars g', g'' on the rod f , at a distance apart equal to that which we desire the cutter C to move. The cutter is run up to the end of its upper stroke. The eye or loop, e , of the rack B, as it slides up the rod f , strikes against the upper collar, g' , raises the rod f , which, by means of the elbow-lever, consisting of the arms s , shaft g , and shifter r , throws the clutch P in contact with the wheel O, which thus becomes locked, through the clutch P, to the shaft g , and receiving motion from the driving-pulley or wheel K through the pinion-wheel L, which is rigidly attached to same sleeve with the wheel K, and which gears into the loose pinion M, which gears into the wheel G, which is rigidly attached to the same sleeve with the pinion L, and turns it, and which, gearing into the wheel O, gives motion to it; and the wheel O, being now engaged with the clutch P, causes the shaft g to revolve, and with it the pinion N, which is rigidly attached to the shaft g , and which, gearing into the wheel F, which is rigidly attached to the shaft h , together with the pinion E, causes the latter to revolve, and, through the rack B, give a downward motion to the cutter C, which, at one stroke, cuts a neat and well-made seat, of the desired depth, in the wheel on the pin d .

When the rack B runs down, so that the eye or loop e , on the rod f , comes in contact with the collar g'' , the clutch P is disengaged from the wheel O, and moved laterally on the shaft g , in an opposite direction, and engages by friction with the pinion L, which, as it moves in an opposite direction from that of the wheel O, will cause the shaft g to revolve in an opposite direction, and, consequently, the pinion N, wheel F, pinion E, and rack B, which will cause the cutter to ascend to the end of its upper stroke.

In the mean time, the wheel having the key-seat cut in it is removed, and another put in its place, which is now ready to be cut, and thus the operation may be continued indefinitely, or until some part of the mechanism becomes deranged, or the cutter needs adjusting or filing.

When desired, the clutch P may be shifted by the handle Q.

In this operation, the wheels or pulleys that are having key-seats cut, fit snug on the pin d . If wheels or pulleys intended for different-sized shafting are to be key-seated, pins of corresponding size must be used.

The cutter C is kept in an upright position by means of a spring, U', or any other suitable device.

In this way we are able to construct a most valuable and efficient machine for cutting key-seats in wheels, pulleys, or similar articles.

Having thus described our invention, what we claim, is—

1. In combination with the slotted pin d , the cutting-tool C, having its front edge provided with saw-teeth, and made tapering longitudinally, for the purpose of feeding forward in descending and cutting a key-seat, substantially as described.

2. In combination with the reciprocating rack-bar B, the adjustable collars g', g'' , or their equivalents, arranged with the shifting-mechanism to operate in the machine, as described, for shortening or lengthening the movement of the cutting-tool C, as set forth.

3. The guard U and spring U', in combination with the cutting-tool C, when arranged as herein described, and for the purpose set forth.

4. The combination of the pulley K and pinion L on the same sleeve, the pinion M, wheel G, and pinion I on the same sleeve, wheel O and pinion N, wheel F and pinion E, attached to same shaft, h , rack B and clutch P, all constructed and arranged as described, for the purpose of giving a reciprocating motion to the cutting-tool C, to cut key-seats, as set forth.

WM. H. SMITH,
ROLLIN S. EDDY.
